UNITED STATES PATENT OFFICE.

FRANK M. FREEBURG, OF PHILADELPHIA, PENNSYLVANIA.

RAILWAY-SWITCH.

1,259,506.

Specification of Letters Patent. Patented Mar. 19, 1918.

Application filed March 24, 1917. Serial No. 157,186.

To all whom it may concern:

Be it known that I, FRANK M. FREEBURG, a citizen of the United States, residing at Philadelphia, in the county of Philadelphia and State of Pennsylvania, have invented 5 certain new and useful Improvements in Railway-Switches, of which the following is a specification.

My invention relates to improvements in 10 railway switches wherein are employed a main rail, a branch rail leading therefrom and vertically adjustable switch rails adapted, when so adjusted to different positions, to control the direction of travel of car 15 wheels relatively to the main and branch rails.

The object of my invention is to provide a 20 novel switch of this character which will permit either switch rail to yield downwardly under the pressure of wheel flanges when the rail is up in the path of the wheel flanges and in position to govern the course 25 of the wheels while passing in one direction and the wheels pass the switch rail in the reverse direction. A further object of my invention is to provide a novel, simple and efficient means for adjusting the switch rails to different positions.

With these and other objects in view, my 30 invention consists in the novel construction and combinations of parts hereinafter fully described and claimed.

In the accompanying drawings illustrating my invention,

35 Figure 1 is a plan of a railway switch embodying my invention.

Fig. 2 is a side elevation thereof, partly in section.

Fig. 3 is a plan of the switch tongues.

40 Figs. 4, 5, 6, 7, 8, 9, 10 and 11 are transverse sections of the switch structure on lines 4—4, 5—5, 6—6, 7—7, 8—8, 9—9, 10—10 and 11—11, respectively, of Fig. 1.

Fig. 12 is a transverse section, showing 45 the switch tongue raising and lowering mechanism, on line 12—12 of Fig. 1.

Fig. 13 is a view similar to Fig. 12, including part of a car wheel and showing the switch parts in a different position.

50 Figs. 14 and 15 are sections on line 14—14 of Fig. 12, Fig. 14 showing the switch tongue in the raised position and Fig. 15 showing the switch tongue in the lowered position.

55 Fig. 16 is a detail showing a portion of

one of the switch tongues and its raising and lowering cam.

Referring to the drawings, 15 designates the frame of the switch structure having the main track groove 16 and the branch 60 track groove 17 formed therein, the grooves 16 and 17 being adapted to receive the car wheel flanges in the usual manner, the branch track groove 17 communicating with the main track groove 16, as shown. On 65 the outside of the grooves 16 and 17 are the tread portions 18 and 19, forming sections of the main and branch rails, respectively, of the switch, and on the inside of the grooves 16 and 17 is the usual guard portion 20. One end of the tread portion or branch rail 19 forms the frog point and the other end thereof is adapted to be connected to additional branch rail sections; and the respective ends of the tread portion or main 75 rail 18 are adapted to be connected to additional main rail sections, in the usual well known manner.

Within the grooves 16 and 17 are two 80 tongues 21 and 22, respectively, having rounded end portions 23 fitted to turn in sockets 24 in the frame 15 in a manner to permit the pointed ends of the tongues to be raised and lowered into and from the paths of the car wheel flanges.

The tongue 21 has a vertical face 23 which, when the tongue is raised, connects the side of the point portion of the branch rail 19, forming one wall of the branch track groove 17 with the side of the tread portion or main 90 rail 18 forming one wall of the main track groove 16, so that when the tongue 21 is up and the tongue 22 is down, the face 23 will direct wheel flanges from the main track 18 to the branch track 19.

The tongue 22 has a vertical face 24 which, when the tongue is raised, forms a continuation of the side of the point portion 19 which forms one wall of the main track groove 16 and prevents wheel flanges 100 from entering the branch track groove 17, when the car wheels pass directly along the main rail 18.

The top of the point end of the tongue 21 is slightly below the top of the tread portions 18 and 19, so that car wheels will not bear upon the tongue 21 when it is raised, the wheels being supported by both tread portions 18 and 19 in passing over the main track groove 16 to and from the branch 110

track. The pivoted ends of the tongues 21 and 22 are always below the paths of the wheel flanges, the upper face of each tongue being inclined upwardly from its pivoted end when it is in the raised position.

The switch tongues 21 and 22 are fitted to slide vertically between walls of the frame 15, and when each tongue is down its upper face forms a continuation of the floor portions of the grooves beyond the ends of the tongue. The tongues 21 and 22 are adapted to abut against and engage each other between the point ends thereof and the point end of the tread portion 19, the upper portions of the tongues 21 and 22 being cut away to form portions of the faces 23 and 24, respectively, and thereby form the pointed ends of the switch rails, as shown. The tongue 21 has a shoulder 25 providing an off-set for the reception of the comparatively blunt, pointed end of the tread portion or frog point 19. The shoulder 25 thus serves to prevent wheel flanges from striking the point of the tread portion 19 when the tongue 21 is raised to direct the wheels from the main track 18 to the branch track 19.

In operating the switch, the tongues 21 and 22 are raised and lowered in alternate succession, and when the tongue 22 is raised an uninterrupted main track groove 16 is presented, and when the tongue 21 is raised an uninterrupted branch track groove 17 is presented, and to thus raise and lower the tongues 21 and 22 I provide the following mechanism:

The tongues 21 and 22, near their point ends, are provided with portions 26 and 27 which extend downwardly into a box-like portion 28 of the switch frame 15. These portions 26 and 27 have openings 29 and 30, respectively, therein; and extending through these openings 29 and 30 is a transverse shaft 31. The outer end of the shaft 31 is fitted to turn in a bearing 32 which extends into a vertical guide slot 33 in a wall 34 of the box-like portion 28. The inner portion of the shaft 31 has a collar 35 formed thereon or secured thereto which is arranged within a vertical guide slot 36 formed in a wall 37 of the switch structure within the box-like portion 28. The guide slots 33 and 36 are adapted to permit the shaft 31 to be moved vertically therein and to prevent displacement of the shaft longitudinally of the switch structure. The bearing 32 and the collar 35 are maintained normally at the upper ends of their slots 33 and 36, respectively, by springs 38 and 39, thereby holding the shaft 31 normally in the horizontal position shown in Fig. 12.

The spring 38 rests upon a screw plug 40 screwed into the bottom of the switch structure, and the upper end of the spring 38 bears directly against the bearing 32. The

spring 39 rests upon a screw plug 41 screwed into the bottom of the switch structure, and the upper end of the spring 39 bears against a block 42 which is slideable within the slot 36 and bears against the bottom of the collar 35 therein.

From the construction just described, it will be understood that the shaft 31 may be depressed from the position shown in Fig. 12 against the action of the springs 38 and 39.

The inner end of the shaft 31 is provided with an upwardly-projecting, heavy arm 43 which is adapted to be moved from the position shown in Fig. 14 to the position 80 shown in Fig. 15 and back again to turn the shaft 31 a quarter revolution from the position shown in Fig. 14 to the position shown in Fig. 15 and back again, for a purpose hereinafter described.

The shaft 31 is provided with cams 44 and 45 which are arranged within the openings 29 and 30 of the switch tongues 21 and 22, respectively. These cams 44 and 45 are adapted to be moved back and forth from vertical to horizontal positions when the shaft 31 is turned a quarter revolution, first in one direction and then in the reverse direction, by operating the arm 43, as previously described. When one cam is moved 95 from the horizontal to the vertical position, the other cam is moved from the vertical to the horizontal position; and when one cam is moved from the vertical to the horizontal position, the other cam is moved 100 from the horizontal to the vertical position, when the arm 43 is operated.

When the cam 44 is moved to the vertical position it raises the switch tongue 21, and when the cam 44 is moved to the horizontal position it lowers the switch tongue 21. When the cam 45 is moved to the vertical position it raises the switch tongue 22, and when the cam 45 is moved to the horizontal position it lowers the switch tongue 22.

When the cams 44 and 45 are moved to lower the switch tongues 21 and 22, respectively, the cams 44 and 45 enter sockets 46 and 47 formed by the openings 29 and 30, respectively, and when the cams 44 and 45 are moved to raise the switch tongues 21 and 22, respectively, the cams 44 and 45 enter sockets 48 and 49 formed by the openings 29 and 30, respectively. Thus it will be seen that the engagement of the cams 115 with these sockets will prevent the accidental turning of the shaft 31 by any pressures that might occur against the switch tongues 21 and 22.

The walls of the openings 29 and 30 and the cams 44 and 45 are so arranged relatively to each other that when the arm 43 is moved from the position shown in Fig. 14 to the position shown in Fig. 15 the switch tongue 21 will be lowered and the 130

switch tongue 22 will be raised, and that when the arm 43 is moved from the position shown in Fig. 15 to the position shown in Fig. 14 the switch tongue 22 will be lowered and the switch tongue 21 will be raised.

The shaft 31 is not only held in the two positions to which it is moved, as just described, by the engagement of the cams 44 and 45 with the walls of the openings 29 and 30, respectively, but it is also held in such positions by the weight of the arm 43 which passes the vertical center each time it is operated to turn the shaft 31 a quarter revolution.

15 To move the arm 43 to turn the shaft 31, as previously described, I provide the following: Pivoted at 50 in the switch structure is an arm 51 provided with a pin 52 which projects into a radial slot 53 in the arm 43. This arm 51 is provided with an opening or socket 54 which is adapted to receive an operating bar 55, as shown in the drawings, whereby the arm 51 may be moved from the position shown in Fig. 14 to the 25 position shown in Fig. 15 and back again. When the arm 51 is thus moved from the position shown in Fig. 14 to the position shown in Fig. 15, the pin 52 will engage the wall of the slot 53 and move the arm 43 from the position shown in Fig. 14 to the position shown in Fig. 15; and when the arm 51 is moved from the position shown in Fig. 15 to the position shown in Fig. 14, the pin 52 will engage the wall of the slot 30 35 53 and move the arm 43 from the position shown in Fig. 15 to the position shown in Fig. 14. The pin and slot connection between the arms 43 and 51 permits the shaft 31 to be depressed against the action of the 40 springs 38 and 39.

The arm 43 is provided with a spring 56, one end of which is connected thereto and the other end of which is connected to a pin 57 projecting over the switch frame 15, 45 which exerts a pull upon the arm 43 and prevents it from resting in a position at dead center over the shaft 31. The weight of the arm 43 always overcomes the action of the spring 56 after it has passed the dead 50 center in moving to either of its positions shown in Figs. 14 and 15.

The springs 38 and 39 hold the shaft 31 normally in the position shown in Fig. 12, and when the shaft is thus held in this 55 position it will be readily understood that by moving the bar 55 to operate the arm 51 the switch tongues 21 and 22 may be readily set to permit car wheels to pass directly along the main track 18 or to pass from the one to the other of the main and branch tracks 18 and 19, respectively.

When the switch tongues 21 and 22 are set with the tongue 22 in the raised position and a wheel passes from the branch track 60 65 19 to the main track 18, the wheel flange will

act upon the top of the switch tongue 22 and thereby depress it and the shaft 31 against the action of the springs 38 and 39, as shown in Fig. 13, and thus permit the easy passage of the wheel over the switch 70 tongue 22, notwithstanding its raised position to control the direction of the movement of car wheels in the reverse direction; and when the switch tongues 21 and 22 are set with the tongue 21 in the raised position 75 and a wheel passes along the main track 18 in the direction of the arrow A, the wheel flange will act upon the top of the switch tongue 21 and thereby depress it and the shaft 31 against the action of the springs 80 38 and 39 and thus permit the easy passage of the wheel over the switch tongue 21, notwithstanding its raised position to control the direction of the movement of car wheels in the reverse direction.

I claim:

1. In a railway switch, the combination of a main rail, a branch rail leading therefrom, a vertically-movable switch tongue adapted to control the passage of car wheels 90 relatively to the main rail and the branch rail, means operative to raise and lower the switch tongue into and from the path of wheel flanges adjacent to said rails, and yielding means supporting the switch tongue 95 and permitting it to be depressed against the action thereof.

2. In a railway switch, the combination of a main rail, a branch rail leading therefrom, a vertically-movable switch tongue 100 adapted to control the passage of car wheels relatively to the main rail and the branch rail, means operative to raise and lower the switch tongue into and from the path of wheel flanges adjacent to said rails, and yielding means supporting the last named means and the switch tongue and permitting them to be depressed against the action thereof.

3. In a railway switch, the combination 110 of a main rail, a branch rail leading therefrom, a vertically-movable switch tongue adapted to control the passage of car wheels relatively to the main rail and the branch rail, a shaft extending beneath the switch 115 tongue, means carried by the shaft and operated to raise and lower the switch tongue when the shaft is turned, a vertically-movable bearing for said shaft, guiding means for said bearing, and yielding 120 means supporting said bearing and permitting the switch tongue to be depressed against the action thereof.

4. In a railway switch, the combination of a main rail, a branch rail leading therefrom, a vertically-movable switch tongue adapted to control the passage of car wheels relatively to the main rail and the branch rail, said switch tongue having an opening 125 therein, a shaft, supporting means for the 130

shaft, and a cam carried by the shaft and adapted to work within said opening and to engage the top of the opening to raise the switch tongue and to engage the bottom 5 of the opening to lower the switch tongue when said shaft is turned.

5. In a railway switch, the combination of a main rail, a branch rail leading therefrom, a vertically-movable switch tongue 10 adopted to control the passage of car wheels relatively to the main rail and the branch rail, said switch tongue having a socket formed therein, a shaft, supporting means for the shaft, and a cam carried by said 15 shaft and adapted to support and control the raising and lowering of the switch tongue when the shaft is turned, said cam being adapted to enter the socket in the switch tongue when raised, and thereafter 20 preventing the turning of the cam and its shaft by downward pressure against the switch tongue.

6. In a railway switch, the combination of a main rail, a branch rail leading therefrom, a vertically-movable switch tongue 25 adapted to control the passage of car wheels relatively to the main rail and the branch rail, said switch tongue having a socket formed therein, a shaft, supporting means 30 for the shaft, and a cam carried by said shaft and adapted to support and control the raising and lowering of the switch tongue when the shaft is turned, said cam being adapted to enter the socket in the 35 switch tongue when raised and thereafter preventing the turning of the cam and its shaft by downward pressure against the switch tongue, and one part of the structure 40 being yieldable and permitting the switch tongue to be depressed against the action thereof.

7. In a railway switch, the combination of a main rail, a branch rail leading therefrom, a vertically-movable switch tongue 45 adapted to control the passage of car wheels relatively to the main rail and the branch rail, said switch tongue having a socket formed therein, a shaft, and a cam carried

by said shaft and adapted to support and control the raising and lowering of the 50 switch tongue when the shaft is turned, said cam being adapted to enter the socket in the switch tongue when raised, and thereafter preventing the turning of the cam and its 55 shaft by downward pressure against the switch tongue, and yielding means supporting the shaft and permitting the switch tongue to be depressed against the action thereof.

8. In a railway switch, the combination 60 of a main rail, a branch rail leading therefrom, a vertically-movable switch tongue, 65 adapted to control the passage of car wheels relatively to the main rail and the branch rail, a shaft, supporting means for the shaft, an arm projecting from the shaft and having a slot therein, and a pivoted arm having a pin projecting into said slot and operative to turn the first named arm and said 70 shaft.

9. In a railway switch, the combination of a main rail, a branch rail leading therefrom, vertically-movable switch tongue adapted to control the passage of car wheels relatively to the main rail and the branch 75 rail, a shaft, an arm projecting from the shaft and having a slot therein, a pivoted arm having a pin projecting into said slot and operative to turn the first named arm and said shaft, and yielding means supporting 80 said shaft and permitting it and the switch tongue to be depressed relatively to the main and branch rails and the first named arm.

10. In a railway switch, the combination 85 of a frame, a shaft adapted to be rocked back and forth, an operating arm for said shaft adapted to move over the center of the shaft when it is rocked, a switch tongue operated by said shaft, and a spring acting 90 against said arm and preventing it from resting at a dead center over said shaft.

In testimony whereof I affix my signature hereto.

FRANK M. FREEBURG.
